UNITED STATES PATENT OFFICE.

ALBERT A. HEYMAN, OF BALTIMORE, MARYLAND, ASSIGNEE TO UNIVERSAL CIGAR MACHINERY CO., INC., OF BALTIMORE, MARYLAND.

METHOD OF FORMING CIGARS.

1,152,022.

Specification of Letters Patent. Patented Aug. 31, 1915.

Application filed November 15, 1913. Serial No. 801,178.

To all whom it may concern:

Be it known that I, ALBERT A. HEYMAN, a citizen of the United States, residing at Baltimore, in the State of Maryland, have 5 invented a new and useful Method of Forming Cigars, of which the following is a specification.

This invention relates to a method of forming cigars, one of the objects of the invention being to produce a plurality of cigars of exactly the same quality, a uniform blend or mixture of tobacco being obtained by one step in the method.

Another object is to provide cigars of uniform size, the blended bunches of tobacco being cut and shaped in a novel manner constituting another step in the method.

Another object of the invention is to produce cigars which, when of one grade or 20 blend, will be identical and without the variation in strength or quality which it has heretofore been practically impossible to avoid.

A further object is to provide a method 25 whereby all cigars of one grade which may be produced, will have the layers of different grades of tobacco arranged in the same sequence, each layer in each cigar being of substantially uniform thickness and being 30 substantially continuous from one end to the other of the cigar so that the draft through all of the cigars will be the same and each cigar will be free of objectionable air spaces such as might be caused by breaks in the 35 layers, and the grain of all of the layers will be extended in the direction of the length of the cigars.

With the foregoing and other objects in view the invention consists in certain steps 40 in the method of producing cigars, which will be hereinafter more fully described and pointed out in the claims.

In carrying out the invention it is designed to use a number of trays or other 45 suitable receptacles each of which is adapted to hold a single layer or thickness of tobacco leaves. Where the cigars to be produced are to be of the same grade of tobacco throughout, each tray will be provided with 50 a single layer of tobacco of the same grade. Where, however, a blend is to be used in the formation of the cigars, certain of the trays

are provided with tobacco of one grade, other trays can be provided with tobacco of another grade, while still other trays can be 55 provided with tobacco of a third grade. Obviously any desired number of grades can be used, one set of trays being employed for each grade. After the layers of tobacco have been trimmed so as not to project beyond the 60 walls of the trays in which they are located, said layers are superimposed in predetermined sequence, first a layer of one grade being deposited and on this a layer of another grade, etc., this procedure being followed 65 until a stack or bundle of desired thickness has been produced with layers arranged in the order desired. Upon the completion of the formation of the stack which, 70 obviously, is made up of substantially unbroken layers, each layer being practically of uniform thickness, the said stack or bundle is divided in the direction of the grain so as to produce separate bunches, each bunch being of such bulk that, when 75 shaped or rolled, it will produce a cigar of the desired thickness. If desired, however, instead of forming a stack or bundle and dividing it into separate bunches, a long narrow stack or bundle can be produced, the 80 same being so proportioned as to obviate the necessity of separating it longitudinally. Upon the completion of the formation of the bunches, the same are cut off into lengths and the said lengths are shaped by rolling 85 them, after which a binder is applied.

It is to be understood that various mechanisms may be employed for carrying out the process hereinbefore outlined and in the accompanying drawings one type of mechanism has been shown more or less diagrammatically.

In these drawings:—Figure 1 is a plan view of a series of trays for receiving layers of tobacco in carrying out the first step of 95 the process. Fig. 2 is a transverse section through conveyer chains upon which the trays are mounted, said trays being shown in elevation and there being shown above the trays trimming knives whereby the tobacco layers are cut off along the edges of the trays in carrying out the second step of 100 the method. Fig. 3 is an elevation of a portion of a case and showing trays therein

whereby the layers of trimmed tobacco may be cured prior to being supplied to the bundle or stack forming mechanism. Fig. 4 is a perspective view of one of the trays 5 in position at one side of the mechanism provided for holding the stack or bundle and for forming the bunches and shaping said bunches. Fig. 5 is a perspective view of a pneumatic conveyer which can be employed for lifting the layer of tobacco from the tray and depositing it within the bundle or stack holder. Fig. 6 is a section through the tray and showing the conveyer in position thereabove. Fig. 7 is a transverse section 10 through the stack or bundle holder and showing several layers deposited therein, the position of the conveyer above the holder being indicated by dotted lines. Fig. 8 is a perspective view of the bundle or stack 20 compressing and severing head. Fig. 9 is an end elevation thereof. Fig. 10 is a plan view of the stack or bundle holder and of the shaping mechanism at the sides thereof. Fig. 11 is an enlarged transverse section 25 through a portion of the stack or bundle holder and showing the compressing and severing head in position immediately subsequent to the compression of the stack or bundle and the separation thereof into separate bunches. Fig. 12 is a perspective view 30 of the cut-off and feeding head used at each side of the stack or bundle holder. Fig. 13 is an enlarged vertical longitudinal section through a portion of the stack holder and 35 showing a bunch projected to position under the cut-off and feeding head and above the shaping mechanism, a binder being shown in position upon said mechanism ready to be delivered to the shaped bunch. Fig. 14 is a view showing diagrammatically, the relative positions of the parts of 40 the shaping mechanism during the feeding of the severed bunch thereto. Fig. 15 is a view similar to Fig. 14 and showing the 45 relative positions of the parts during the shaping of the bunch and the application of the binder thereto. Fig. 16 is a view similar to Figs. 14 and 15 and showing the relative positions of the parts during the 50 discharge of the shaped bunch after the application of the binder thereto. Fig. 17 is a view partly in elevation and partly in section showing modified means for depositing layers of tobacco successively within the 55 stack holder. Fig. 18 is a similar view showing another means for depositing the layers in the stack holder. Fig. 19 is a side elevation showing the means whereby layers can be lifted successively from a continu- 60 ously moving conveyer and carried to the stack holder. Fig. 20 is a view partly in section showing a stack holder which can be of considerable length and in which may be formed a stack which does not require 65 separation into bunches but which, instead,

is of the same cross sectional area as the bunch which might be produced by longitudinal separation as hereinbefore set forth. Fig. 21 is a plan view of the meeting ends 70 of two trays so shaped that, when trimmed, the layers, when superimposed, will produce a stack having serrated ends. Fig. 22 is a detail view of a combined cutoff and feeding head utilizing a serrated knife whereby, when the bunches are cut off in lengths, they will be formed in one end with V-shaped incisions, and at their other ends with tapered projections whereby, in the 75 shaping of the bunches, said bunches can be formed with tapered ends without producing undesirable compression of the tobacco at the ends of the bunches. 80

Referring to the figures by characters of reference 1 designates trays having foraminous bottoms and the trays may be supported by a conveyer 2, the chains of which have been shown in section at 3 in Fig. 2. The trays are adapted to be placed close together and tobacco leaves are arranged in a layer of uniform thickness over all the 90 trays. Suitable severing and trimming means, such as knives 4 depending from a vertically movable frame 5, may be supported above the trays so that, by depressing said means, any portions of the contents of the trays which may project beyond the exposed or outer edges of said trays will be cut off and the contents of the several trays will be severed without waste. If the trays are provided with straight edges, the leaves 100 of tobacco carried by the trays will thus be cut along the straight edges whereas should the trays be provided with toothed or serrated ends, as shown at 6 in Fig. 21, serrated knives or the like can be used so that 105 the contours of the edges of the layers of tobacco will correspond with the contours of the edges of the trays.

A curing rack for the reception of the trays has been indicated at 7 and can be of 110 any construction desired. The conveyer 2 is adapted to carry the trays close to or up to a stack holder preferably in the form of a rectangular frame 8, the bottom portion of this frame being sub-divided into parallel channels by partitions 9 arranged in pairs, the partitions of each pair being slightly spaced apart to form a knife receiving recess 10 extending longitudinally of the partitions. Bunch receiving channels 11 are formed between the pairs of partitions. The bottom of the stack holder is closed, as shown at 12. Each pair of partitions 9 is surrounded longitudinally by an endless belt 13 mounted on rollers 14 at the 115 ends of the partitions and each belt moves oppositely to the direction of movement of the next adjoining belt so that adjoining belts will thus coöperate to eject longitudinally any bunches which may be deposited 120 125 130

in the channels 11, as will be apparent by referring to Fig. 10 wherein the direction of movement of the bunches under the action of the belts, has been indicated by arrows.

Various means may be provided for removing the layers of tobacco from the trays 1 and depositing them in the stack holder. One means employed consists of a rectangular hollow conveyer head 15 the bottom face of which is provided with a foraminous cover 16 coextensive with the tray. A flexible tube 17 extends from the interior of the conveyer head to suitable suction means and, by setting up a suction through the head 15 and tube 17 and then placing the head upon the layer of tobacco supported by a tray, it will be seen that the force of the suction will cause the layer of tobacco to adhere to the foraminous face 16 so that, when the head 15 is shifted away from the tray, the layer of tobacco will be carried therewith. The head 15 can then be placed directly over the stack holder and, when the suction through the tube 17 is broken in any suitable manner, the supported layer of tobacco will be released and will thus gravitate into the stack holder.

Instead of utilizing a conveyer such as shown in Figs. 5 and 6, a tray receiver 18 may be hingedly connected, as at 19, to one wall of the stack holder and this tray holder, which is closed at its sides and bottom, may be provided with a flexible tube 20 opening thereto and connected to a suitable suction device. The tray containing the layer of tobacco to be deposited in the stack holder is adapted to be placed upon the receiver 18 and, when suction is set up through the tube 20, the layer of tobacco supported by the tray will be caused to adhere thereto so that the receiver 18 can thus be swung about its hinge 19 so as to assume an inverted position above the stack holder 8, this movement being effected without displacing any part of the layer of tobacco relative to the tray 1. As soon as the tray has been inverted in this manner, the suction through tube 20 can be broken, whereupon the layer of tobacco will be released and will gravitate into the stack holder 8.

Another means for directing the layers of tobacco into the stack holder has been shown in Fig. 18. By referring to this figure it will be seen that an open tray supporting frame 21 is hingedly connected, as at 22, to the stack holder and the tray 1 on which the layer of tobacco is arranged, placed in this holder. By swinging the holder 21 quickly to an inverted position, the pressure of air against the layer of tobacco will cause said layer to adhere to the foraminous portion of the tray so that the said layer will thus be brought to position above the holder 8 without becoming displaced relative to the

tray and, as soon as the tray is brought to a stand above the holder 8, the layer of tobacco will gravitate into the holder.

In Fig. 19 I have illustrated a conveyer 22 which can be operated either continuously or intermittently and trays may be carried by this conveyer so as to be brought successively into position under a conveyer head 23 such as shown in Figs. 5 and 6 or, if desired, a uniform layer of tobacco can be arranged on this conveyer, said layer being divided into lengths and said lengths being brought successively into position under the conveyer head 23 so that they will be lifted successively from the conveyer and carried to the stack holder.

After a predetermined number of layers of tobacco have been placed in the holder 8, these layers either being of the same kind of tobacco or of different kinds, as before pointed out, the compressing and severing head shown in detail in Figs. 8 and 9, is brought into play. This head is made up of a backing 24 having a series of parallel compressing cleats 25 constituting followers, these cleats or followers being spaced apart sufficient distances to receive between them the pairs of partitions 9 when the head is lowered into the holder 8. Supported between the cleats or followers 25 are severing knives 26, these knives extending downwardly below the cleats or followers and being adapted, when the head is lowered, to enter between the partitions of each pair.

With the stack made up of the superimposed layers of tobacco resting on the partitions 9, the compressing and severing head is lowered so as thus to cause the knives 26 to cut through the stack, these knives at the same time entering the spaces 10 while the cleats or followers 25 will press the bunches thus formed, into the channels 11, as shown in Fig. 11. Thus each of the plurality of bunches thus formed will be a duplicate of the other bunches, said bunches being made up of the same number of layers arranged in the same sequence, each layer of each bunch being continuous throughout the length and width thereof and the grain of each layer being extended in the direction of the length of the bunch.

After the compressing and severing head has been raised out of engagement with the bunches produced in the manner set forth, the belts 13 are set in motion so as to shift the bunches longitudinally in the directions indicated by the arrows in Fig. 7. Thus alternate bunches will be projected beyond one side of the holder 8 while the remaining bunches will be projected beyond the other side of the holder 8.

Located adjacent the sides of the holder 8 so as to be overhung by the bunches when projected from the holder, are devices for shaping those portions of the bunches sup-

plied thereto. This shaping mechanism has been indicated generally at 27 and is adapted to be fed by combined cut-off and feeding means. In Figs. 12 and 13, a combined cut-off and feeding head has been shown in detail, it being understood that one of these heads is to be located at each side of the holder 8. Said head includes a backing 28 having depending cleats or followers 29 which are parallel and located normally above the paths of the projecting portions of the bunches. Those ends of the cleats or followers 29 nearest the holder 8 are provided with cut-off blades 30 so that, when the cut-off and feeding head is moved downwardly, the blades 30 will cut off the projecting portions of the bunches close to the holder 8 while the cleats or followers 29 will press the severed portions down into the shaping mechanism 27.

The shaping mechanism is made up of several units along each side of the holder 8, and as the units are duplicates, it is deemed necessary to describe only one of them. As shown in Figs. 13, 14, 15 and 16, each unit is made up of an eccentrically mounted roller 31 arranged in the same horizontal plane with a roller 32 on which is mounted an inclined endless foraminous conveyer 33. The upper or outer flight of this conveyer travels over the open face of a suction box 34 the interior of which is connected by a tube 35 to a suitable suction device. The suction through the conveyer 33 and the box 34 is normally cut off in any preferred manner, as by means of a valve 35. The greatest distance between the roller 32 and the eccentric roller 31 is substantially equal to the width of the channels 11 and the pass formed between these two rollers 31 and 32 is located directly under the projecting portion of one of the bunches formed in the holder 8.

An eccentrically mounted roller 37 is adapted to be shifted horizontally into or out of position above the center of the pass between the rollers 31 and 32 and another eccentrically mounted roller 38 is adapted to be shifted horizontally into or out of position under the center of the pass between the rollers 31 and 32. These rollers 31, 37 and 38 and the elevator 33 can be rotated in any desired manner and it is not deemed necessary to illustrate or describe mechanism provided for that purpose. It need only be stated that before the cut-off and feeding heads are moved downwardly as hereinbefore described, the upper concentric rollers 37 of the several units are shifted horizontally out of position above the passes between the rollers 31 and 32 so that, when the cut-off and feeding heads are lowered, the severed lengths will be pressed downwardly into the passes between the rollers 31 and 32 and onto the rollers 38. The position of the material immediately prior to

being severed and depressed is illustrated in Fig. 13 while the position of the severed portion of the bunch when depressed into position between the rollers 31 and 32 has been illustrated in Fig. 14. As soon as the severed portions have been seated in the shaping units, the rollers 37 are shifted horizontally back to their initial positions, one of the units being thus illustrated in Fig. 15. The several rollers are then rotated simultaneously and, by reason of the fact that they are eccentrically mounted, they will operate to grip, roll and release the bunch so that the action set up will be substantially like that produced by the hand of a person engaged in forming cigars, it being customary for such a person to compress the bunch in the hand, then open the hand and again compress the bunch, this action causing the bunch to gradually rotate in the hand as it is successively gripped or compressed. After the bunch has been compressed and rolled until the desired shape has been obtained, a binder is placed obliquely upon the upper or outer face of the conveyer 33 and suction is set up through the box 34 and tube 35 so that the binder will thus be caused to adhere to the conveyer. As the conveyer is moving continuously during the rolling of the severed portion of the bunch it will be seen that as soon as the binder is placed on the conveyer and suction is set up, the said binder will be caused to move upwardly into the path formed between the conveyer and the rolled bunch. By placing an adhesive upon the upper corner of the binder it will stick to the bunch so that the said binder will wrap around the bunch during the further rotation thereof, there being another portion of adhesive upon the lower corner of the binder so that, upon the completion of the binding operation, the said binder will remain fastened in place. As soon as the binder has been applied in the manner described, the lower roller 38 is shifted horizontally from under the shaped bunch and said bunch, having the form of a cigar, will drop into a chute 39 or other receiver from which it can be removed and a finishing wrapper placed thereon, whereupon the cigar will be ready for use.

It is to be understood of course that the rollers 31, 37 and 38 can be so shaped as to give the cigars any desired longitudinal contour. Where the ends of the cigars are to be tapered it is desired to remove some of the tobacco therefrom so that there will not be undesirable compression of the ends of the cigar. In order to effect this result the trays can be provided with serrated ends as shown at 6 in Fig. 21 and instead of providing straight blades 30 upon the cut-off and feeding heads, V-shaped blades can be used, as shown at 40 in Fig. 22 so

that one end of each severed portion of a bunch will be V-shaped while the other end of said severed portion will be formed with a V-shaped recess. Thus tapering of the 5 ends of the severed portion of the bunch for the purpose of producing a cigar having tapered ends will not result in undesirable compression of the tobacco at the ends, and consequently, the draft through the cigar 10 will not be interfered with.

As before stated, instead of utilizing a broad stack made up of layers and subsequently cutting the stack longitudinally to form separate bunches, the layers can be 15 formed in a narrow stack of the width of an ordinary bunch. Mechanism for this purpose has been shown in Fig. 20 wherein a holder 41 has been shown provided, at its sides, with belts 42 the adjoining flights of 20 which are adapted to move in the same direction. The top of the holder is open and an endless conveyer 43 is provided for supplying a continuous layer of tobacco to the top of the holder. As the sheet or layer of 25 tobacco extends over the holder 41, a combined cut-off and presser head 44 is moved downwardly so as to cut off a strip of tobacco equal in width to the width of the space in the holder. By reciprocating the 30 head 44 vertically the layer of tobacco supplied to the holder can be quickly cut into strips which will be deposited one upon the other in the holder. The belts 42 can then be actuated to shift the bunch thus formed 35 longitudinally out of the holder 41 after which said bunch can be cut off in lengths and the various lengths shaped in the manner hereinbefore described.

It will be obvious of course that mechanism other than that herein described can 40 be used for carrying out the various steps of the process constituting the present invention and for that reason it has not been deemed necessary to enter into a detailed 45 explanation of the construction of the various parts or of the means whereby they may be actuated in proper succession or timed relation.

It has been found that by cutting from 50 the stack bunches of slightly greater width than those otherwise produced and then rolling the bunches spirally instead of in the manner shown, beneficial results can be obtained.

55 Furthermore while layers can be superimposed to form stacks, it is to be understood that each layer before being placed in a stack can be of the same size as or smaller than the bunch to be formed so that the resultant stack will form either a complete 60 bunch or a part of a bunch. The term "stack" as used in the claims is designed to designate either a series of superimposed layers forming a bunch or a part of a bunch, 65 or forming a pile to be cut into bunches.

What is claimed is:—

1. The herein described step in the method of producing a plurality of cigars of equal quality, which includes first arranging filler stock in separate substantially unbroken layers of substantially uniform thickness and area, each layer being formed of a plurality of leaves of substantially the same grade, then superimposing the layers bodily to form a stack, and then cutting through the 75 stack to form bunches of uniform size.

2. The herein described step in the method of producing a plurality of cigars of equal quality, which includes first arranging the filler stock in separate substantially unbroken layers of substantially uniform thickness and area, each layer being formed of a plurality of leaves of substantially the same grade, the grain of the stock of each 80 layer being extended in the same general direction, then superimposing the layers bodily to form a stack, the grain of all the layers being extended in the same general direction, and then cutting through the stack 85 to form bunches of uniform size.

3. The herein described step in the method of producing a plurality of cigars of equal quality, which includes first forming the stock in layers, each layer being formed of a plurality of leaves of substantially the 90 same grade, the stock of one layer being different from the stock of another layer and each layer being substantially unbroken and substantially uniform in thickness, all of the layers being coextensive, and then conveying the layers bodily in predetermined 95 succession to a stack holder.

4. The herein described step in the method of producing a plurality of cigars of equal quality, which includes first arranging stock 105 in separate substantially unbroken layers of substantially uniform area and thickness, each layer being formed of a plurality of leaves of substantially the same grade, then moving the layers bodily to superimpose 110 them to form a stack, cutting through the stack to form bunches of uniform size, and subjecting the severed bunches to the action of shaping rollers.

5. The herein described method of producing a plurality of cigars of equal quality, which includes first arranging stock in separate substantially unbroken layers of substantially uniform area and thickness, each layer being formed of a plurality of leaves 115 of substantially the same grade, then moving the layers bodily to superimpose them to form a stack, then cutting through the stack to form bunches of uniform size, subjecting the severed bunches to the action of shaping 120 rollers, and feeding a binder to each bunch while acted upon by the rollers.

6. The herein described method of producing a plurality of cigars of equal quality, which includes first arranging stock in sepa- 130

rate substantially unbroken layers of substantially uniform thickness and area upon invertible foraminous trays, each layer being formed of a plurality of leaves of substantially the same grade, then holding the layers in engagement with the trays by air pressure during the inversion of the trays in predetermined succession to deposit the layers in a stack holder, and releasing the layers from the inverted trays when positioned above the stack holder by relieving the layers from the air pressure.

7. The herein described method of producing a plurality of cigars of equal quality, which includes first arranging the stock in separate substantially unbroken layers of substantially uniform area and thickness, each layer being formed of a plurality of leaves of substantially the same grade, then moving the layers bodily to superimpose them to form a stack, then cutting through the stack to form bunches of uniform size, then projecting the bunches longitudinally from their original positions, severing the projecting portions of the bunches, and rolling the several portions about their longitudinal axes.

8. The herein described method of producing a plurality of cigars of equal quality, which includes first arranging the stock in separate substantially unbroken layers of substantially uniform area and thickness, each layer being formed of a plurality of leaves of substantially the same grade, then separately and bodily moving the layers to superimpose them to form a stack, then cutting through the stack to form bunches of uniform size, then projecting the bunches longitudinally from their original position, severing the projecting portions of the bunches, and subjecting the severed bunches to the action of eccentrically mounted rollers to shape the bunches.

9. The herein described method of producing a plurality of cigars of equal quality, which includes first arranging the stock in separate substantially unbroken layers of substantially uniform area and thickness, each layer being formed of a plurality of leaves of substantially the same grade, then separately and bodily moving the layers to superimpose them to form a stack, then cutting through the stack to form bunches of uniform size, then projecting the bunches longitudinally from their original positions, severing the projecting portions of the

bunches, then rolling the severed portions about their longitudinal axes, and feeding a binder to the severed portions while subjected to the action of the rollers.

10. The herein described step in the method of producing a plurality of cigars of equal quality, which includes first arranging filler stock in separate substantially unbroken layers of substantially uniform thickness, each layer being formed of a plurality of leaves of substantially the same grade, then superimposing the layers bodily to form a stack, and then cutting through the stack to form bunches of uniform size.

11. The herein described step in the method of producing a plurality of cigars of equal quality, which includes arranging a plurality of holders close together, spreading tobacco leaves over all the holders to form a single layer of uniform thickness and quality, severing the layer along the meeting edges of the holders, thereby to divide the layer into separate sections without waste, and then superposing one of said sections upon another.

12. The herein described step in the method of producing a plurality of cigars of equal quality, which includes arranging a plurality of holders close together in separate groups, spreading tobacco leaves of one grade over all of the holders of one group to form a single layer of uniform thickness and quality, spreading tobacco leaves of another grade over all of the holders of the other group to form a single layer of uniform thickness and quality, and severing each layer along the meeting edges of its holders, thereby to divide the layer into separate sections without waste, and then superposing a section of one layer upon a section of the other layer.

13. In a cigar machine, the process of making cigar bunch fillers, comprising arranging leaves and portions thereof in a substantially unbroken layer substantially of the thickness of a single leaf, said leaves and portions thereof being of substantially uniform grade, and cutting from said layer substantially uniform sections.

In testimony that I claim the foregoing as my own, I have hereto affixed my signature in the presence of two witnesses.

ALBERT A. HEYMAN.
